LLC; James Stevens(57) **CLAIM**

The ornamental design for a heated brush, as shown and described.

DESCRIPTION

FIG. 1 is a perspective view of a heated brush showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is an enlarged top plan view thereof;

FIG. 8 is an enlarged bottom plan view thereof; and,

FIG. 9 is an enlarged view of the encircled portion in FIG. 8.

The equal-length broken lines depict portions of the heated brush that form no part of the claimed design.

The dash-dot broken lines in FIG. 8 and FIG. 9 illustrate the boundaries of the enlarged view indicators and form no part of the claimed design.
